UNITED STATES PATENT OFFICE.

SOLOMON BRUCK, OF LOS ANGELES, CALIFORNIA.

DESIGN FOR AN ADVERTISING BADGE.

Application filed December 18, 1923. Serial No. 8,082. Term of patent 14 years.

To all whom it may concern:

Be it known that I, SOLOMON BRUCK, a citizen of the United States of America, residing at the city of Los Angeles, in the State of California and United States of America, have invented a new, original, and ornamental Design for an Advertising Badge, of which the following is a specification, reference being had to the accompanying drawing, forming part thereof.

I claim:

The ornamental design for an advertising badge as shown, and described.
